[57] CLAIM

The ornamental design for a combined pen holder and ink stand, as shown and described.

DESCRIPTION

FIG. 1 is a top plan view of a combined pen holder and ink stand showing my new design;
FIG. 2 is a side elevational view;
FIG. 3 is a bottom plan view; and
FIG. 4 is a central vertical section through the combined pen holder and ink stand showing the ink reservoir and the pen receiver.
